F. G. Fischer,

Attorney

UNITED STATES PATENT OFFICE.

ANDREW H. STONE, OF KANSAS CITY, MISSOURI.

EXTENSION TABLE.

Application filed July 5, 1923. Serial No. 649,446.

To all whom it may concern:

Be it known that I, ANDREW H. STONE, a citizen of the United States, residing at Kansas City, in the county of Jackson and State of Missouri, have invented certain new and useful Improvements in Extension Tables, of which the following is a specification.

My invention relates to improvements in extension tables which may be used to advantage in libraries, parlors, dining rooms, or wherever it is desirable to have a table that can be adjusted to compact form or extended to give additional capacity when needed.

15 The table embodies one or more foldable leaves consisting of sections which are hinged together, so that when not in use they may be folded and supported underneath the top of the table, said leaves being at 20 all times attached to the table to prevent their loss and also to provide a table so constructed that it may be easily and quickly operated.

The invention further provides a plurality of slideable leaves which may be extended to permit the foldable leaves to be adjusted to active position, or contracted after the foldable leaves have been adjusted to inactive position.

30 An important feature resides in novel frictional locking mechanism whereby the slideable leaves may be reliably secured in their different positions.

Another feature resides in means for adjusting the leaves vertically to bring them on a level, so that the top surface of the table will be of uniform height throughout.

Other features will hereinafter appear, and in order that the invention may be fully understood, reference will now be had to the accompanying drawings, in which:

Fig. 1 is an inverted plan view of the table in extended position.

Fig. 3 is a cross section of the table on line III-III of Fig. 1.

Fig. 4 is an enlarged fragmentary cross section on line IV—IV of Fig. 1.

50 Fig. 5 is an enlarged fragmentary cross section on line V—V of Fig. 1.

Fig. 6 is an enlarged fragmentary cross section on line VI—VI of Fig. 1.

Fig. 7 is a broken plan view of a modified form of table.

Form of table.

Fig. 8 is a fragmentary section on line VIII-VIII of Fig. 7.

In carrying out the invention, I employ a depending rim 2 and a frame consisting of longitudinal members 4 and 5 and transverse members 6. The longitudinal members 4 are removably secured to the rim 2 by suitable means such as screws 7, while the transverse members 6 are secured to the longitudinal members 4 and 5 by suitable means such as screws 8. The two endmost transverse members 6 are provided at their undersides with legs 9. The frame above described and its attachments hereinafter referred to can be fitted into any table with a rim 2 when it is desired to convert such table into an extension table. 65 70

10 designates a pair of slidable leaves which constitute the table top when reduced to its most compact form. Said slidable leaves 10 are provided at their undersides with guides 12, which run in longitudinal grooves 14 in the frame members 5. 75

16 designates pairs of foldable leaves adapted to be disposed between the slidable leaves 10 when the table top is extended as disclosed by Figs. 1 and 2, or folded beneath said slidable leaves 10 as shown by dotted lines Fig. 3, when the table top is contracted. The two sections of each foldable leaf 16 are operably connected by hinges 18 and one section of each leaf is provided with a bearing 20 which is swiveled upon a rod 22. 80 85

The rod 22 is mounted at its ends in plates 24 having slots 26 to receive screws 28, whereby said plates 24 are adjustably secured to the two endmost transverse members 6, so that the foldable leaves 16 may be adjusted vertically to bring them on a level, when extended, with the slidable leaves 10. The rod 22 is mounted at intermediate points in plates 23, having slots 25, to receive screws 27, whereby said plates 23 are adjustably secured to blocks 29, so that they may be adjusted vertically with the plates 24. The blocks 29 are fixed to the transverse frame members 6.

When folded the free ends of the lowermost sections of the leaves 16 rest upon inclined guides 30, which guide said lowermost sections upwardly over the adjacent longitudinal member 5 when the free ends of the uppermost sections are swung upwardly by hand over the opposite longitudinal member 5 to the full line position disclosed by 110

Fig. 3. The guides 30 are fixed to a bar 32 secured to the undersides of the two intermediate transverse frame members 6.

Each slideable leaf 10 is provided with a fixedly-mounted stop 34. The stops 34 limit the outward movement of the leaves 10 by contacting the two endmost transverse members 6, and also coact with dowels 36 in supporting the leaves 16, when extended so that they cannot sag at their hinged joints 38.

Each slideable leaf 10 is provided at its underside with a fixed rail 40, spaced slightly below the leaf by an intervening filler strip 41. The upper surface of the rails 40 are engaged by the inturned upper ends 42 of members 44 loosely connected to the two endmost transverse frame members 6 by suitable means such as screws 48 passing through the slotted portions 50 of said members 44. Each member 44 has an inclined surface 52 spaced beneath the adjacent rail 40 and slidably engaged by the transverse portion 54 at one end of a locking element 56, provided at its opposite end with a handle 58 and mounted in a guide 60 secured to the underside of the adjacent transverse frame member 6.

The handles 58 extend to within convenient reach at one side of the table and when pulled outwardly in the direction of the arrow, Fig. 4, the transverse portions 54 of the locking elements 56 travel up the inclines 52 and frictionally engage the undersides of the rails 40 to hold the leaves 10 at any point of their inward or outward movement.

In order to prevent the slideable leaves 10 from fitting too loosely or too tightly upon the frame 2, I provide adjusting mechanism consisting of members 62 and bolts 64 which latter are connected to the former by heads 66 and nuts 68.

The members 62 have inturned ends 70 overlapping the upper surface of the rails 40, so that when the nuts 72 on the bolts 64 are tightened to draw the members 62 downwardly, they in turn will pull the leaves 10 downwardly upon the frame 2 until all lost motion is substantially eliminated. Should the leaves 10 fit too tightly on the frame 2 the nuts 72 are loosened and the bolts 64 are pushed upwardly to loosen the grip of the members 62 upon the rails 40. The bolts 64 extend through blocks 74 fixed to the inner surface of the ends of the rim 2 and provided with recesses 76 in which the members 62 operate.

The longitudinal members 5 are provided at their ends with recesses 78 communicating with the upper sides of the grooves 14 and through which the guides 12 may pass should it be desirable to remove the leaves 10 from the frame 2 for any cause. Preparatory to removing the leaves 10, the stops

34 are removed and said leaves 10 are then slid apart until the guides 12 register with the recesses 78. The nuts 72 are then removed from the bolts 64, so that the same and their attachments may be lifted off with the leaves 10.

The operation briefly stated is as follows: When the table is in extended position as disclosed by Fig. 1, the leaves 10 are firmly locked against the adjacent foldable leaves 16 by pulling the locking members 56 outwardly in the direction of the arrow, Fig. 4. When it is desired to contract the top of the table to its most compact form all of the leaves 16 are folded to the position disclosed by dotted lines, Fig. 3, and the leaves 10 are slid toward each other until they abut and the slides 12 abut stops 80 secured to the central portions of the longitudinal frame members 5 to center the leaves 10 upon the frame. The locking members 56 which were previously slid inwardly to release the leaves 10 preparatory to sliding the same toward each other, are then tightened as before stated to again lock said leaves 10 in their contracted position.

Of course when desired only one or two of the foldable leaves may be opened to active position instead of all three as disclosed by Fig. 1.

In the modified form disclosed by Figs. 7 and 8, the slideable leaves 10^a are provided at their undersides with keepers 44^a having depending portions 45 which are brought together when the leaves 10^a are moved inwardly towards each other as disclosed by Fig. 7.

The leaves 10^a are then secured by the V-shaped terminal 54^a which engage the downturned ends 45 of the keepers 44^a. The V-shaped terminal 54^a is on a lock member 56^a provided with a handle 58^a, and slidably mounted in guides 60^a and a slotted plate 60^b.

Having thus described my invention, what I claim and desire to secure by Letters Patent, is:

1. In a table of the character described, a frame, a leaf slidably mounted on said frame, a rail fixed to said leaf, a member mounted on the frame having an inclined surface and overlapping said rail, and means guided by said inclined surface into frictional engagement with the rail to secure the leaf at any point of its movement.

2. In a table of the character described, a frame, leaves slidably mounted on said frame, rails fixed to said leaves, members mounted on the frame having inclined surfaces and overlapping said rails, foldable leaves arranged to fold beneath the slideable leaves when the same are slid together, or be extended between said slideable leaves when the same are slid apart, and locking elements projecting between the rails and said

inclined surfaces to travel on the same and draw the overlapping portions firmly into engagement with said rails and lock the same and the slideable leaves at any point of their movement.

3. In a table of the character described, a frame, a leaf adjustably mounted on said frame, a rail fixed to said leaf, a member loosely connected to said frame and having

inturned ends overlapping the rail and an inclined surface underlying said rail, and a locking member slideable on said inclined surface to cause the inturned ends to frictionally engage the rail and thereby lock the leaf at any point of its adjustment.

In testimony whereof I affix my signature.

ANDREW H. STONE.
